UNITED STATES PATENT OFFICE

2,257,435

MOTOR-OPERATED VALVE

Carl Thumim, Yeadon, Pa., assignor to General Electric Company, a corporation of New York

Application October 15, 1940, Serial No. 361,295

6 Claims. (Cl. 137—139)

My invention relates to a high-pressure motor-operated valve which closes at very high speed and is particularly adaptable for use in controlling the fluid used with high-voltage circuit breakers of the fluid blast type.

In circuit breakers of the fluid-blast type and specifically in air-blast circuit breakers, it is necessary to provide a source of air under pressure for arc-extinguishing purposes. For uniform operation of the circuit breaker, it is desirable that this source of air be maintained at substantially a constant pressure. Where air-blast circuit breakers are to be used out of doors, particularly in a cold climate, it is necessary to remove the moisture therefrom which may be accomplished by compressing the air to a very high pressure of the order of one thousand pounds per square inch and thereafter cooling the same to condense the moisture contained therein. It is then necessary to reduce this pressure for use in the air-blast circuit breakers to some value of the order of three hundred and fifty pounds per square inch or less. Difficulties have been encountered in obtaining means for controlling this reduction of pressure and holding constant pressure on the low side so that a source of air under substantially constant pressure is available for satisfactory operation of an air-blast circuit breaker.

In order to control this pressure reduction, it has been suggested to use electrically operated shut-off valves controlled by a pressure switch. However, a solenoid-operated valve for controlling such high pressures requires a great deal of power to operate and, furthermore, is not sufficiently fast in its operation since such a valve must close almost instantly upon the pressure being attained in view of the large difference in pressure between the high and low pressure systems. An electric motor-driven valve would be satisfactory from the standpoint of the power required to operate but would be far too slow to maintain a substantially constant pressure on the low-pressure side. It would be desirable to provide a valve which would close instantly when the proper pressure is attained on the low-pressure side so as to prevent spilling over of air from the high to the low-pressure side after the proper pressure has been obtained. The opening time of such a valve would not be important but it would be desirable that the valve be so constructed and arranged that, if the proper pressure is attained during the opening of the valve, instant closing thereof will occur even though the full open position has not yet been attained.

Accordingly, it is an object of my invention to provide a new and improved high-pressure valve which will control the flow of fluid between a high and a low-pressure system and maintain substantially constant pressure on the low-pressure system.

It is another object of my invention to provide a motor-operated valve which will close instantly under certain conditions regardless of whether or not the opening operation has been completed.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a perspective view of a motor-operated control valve embodying my invention, Fig. 2 is a schematic diagram showing the valve in the open position, and Fig. 3 is a view similar to Fig. 2 showing the valve at the instant of closing.

25 Referring now to the drawing, I have illustrated generally a valve 10 which is connected to a high-pressure system through conduit 11 and to a low-pressure system through conduit 12. The specific form of valve 10 forms no part of my invention and valve 10 may be any of the types of valves well known to those skilled in the art, such, for example, as a balanced and packed piston type of valve having a reciprocally arranged valve stem 13.

30 In order to operate valve 10, a T-shaped crank 14 is provided, pivotally mounted in the center to a fixed support 15. One leg of crank 14 is operatively connected to valve stem 13 at 16 while the second leg is operatively connected through pin 17 and rollers 18 to compression springs 19 which tend to rotate T-shaped crank 14 in the counter-clockwise direction to close valve 10. The third or middle leg of T-shaped crank 14 is operatively connected at 20 to a collapsible thrust transmitting linkage and more specifically to link 21 of a toggle generally indicated at 22. The other link 23 of toggle 22 is connected at 24 with an extension 25 of crank or pivotally mounted member 25. Pivotally mounted member 25 is suitably supported at either end 25' thereof on fixed supports, not shown, and is normally biased in a clockwise direction by spring means 26.

35 Pivotally mounted member or crank 25 is provided with an arm 27 for supporting an armature 28 which is adapted to close the magnetic

circuit of an electromagnetic means such as solenoid 29 when in the position indicated in Figs. 1 and 2. Solenoid 29 is provided with a suitable core 30 with which armature 28 cooperates. When solenoid 29 is energized, armature 28 is attracted thereto so as to hold or latch pivotally mounted member or crank 25 in a stationary fixed position, thus providing a fixed pivot 24 for one end of toggle 22.

When pivotally mounted member or crank 25 is held stationary by electromagnetic means 29 and toggle 22 is in the overcenter position of Figs. 1 and 2, valve 10 is held in its open position against the bias of springs 19. In order to limit the overcenter travel of toggle 22, a suitable extension 31 is provided on link 21 which engages a stop 32 on link 23, thus providing a suitable locking means. A suitable spring means 33 is provided normally to bias toggle 22 to the undercenter position. Whenever electromagnetic means or solenoid 29 is deenergized, armature 28 is released and pivotally mounted member or crank 25 is free to rotate on pins 25'. As soon as this occurs, spring means 19 cause a counterclockwise rotation of T-shaped crank 14 and, consequently, closing of valve 10. Furthermore, toggle 22 is no longer held in the overcenter position by the force of springs 19 and, consequently, spring 33 causes the toggle to assume the undercenter position shown in Fig. 3.

In order to open solenoid-operated valve 10, I provide a suitable electric motor 34, which is preferably connected through suitable reduction gearing and shaft 35 to crank 36 keyed to the end of shaft 35. Crank 36 is provided with a roller 37 which is arranged to engage with an extension 23' of toggle link 23 so that rotation of crank 36 will force toggle 22 to the overcenter position after which it snaps further over center by the action of springs 19 until it strikes the self-contained stop embodying members 31 and 32. Whenever valve 10 is closed, spring means 26 tends to move pivotally mounted member 25 so that armature 28 is in a position to be held by electromagnetic means or solenoid 29 when the latter is energized.

In order to control the operation of solenoid 29 and electric motor 34, I have provided a suitable control circuit by means of which solenoid 29 and electric motor 34 are connected in parallel to a suitable source of power 38 through a pressure switch 39 which is connected in the low-pressure circuit. Whenever the pressure in the low-pressure system falls below a predetermined value, pressure switch 39 is closed, as shown in Figs. 1 and 2, to energize solenoid 29 and motor 34. As soon as the proper pressure has been attained in the low-pressure system, pressure switch 39 opens deenergizing the solenoid and motor 34.

The operation of the arrangement disclosed in Figs. 1 to 3 will be understood by those skilled in the art in view of the detailed description included above. Referring now to Figs. 1 and 2, with the valve in the open position by virtue of the overcenter position of toggle 22, it will be observed that the disposition of the valve will be maintained as long as pressure switch 39 remains closed. As soon as the predetermined pressure has been attained, pressure switch 39 opens, as shown in Fig. 3, to deenergize electromagnetic means or solenoid 29 and motor 34, whereupon pivotally mounted member 25 rotates in a counterclockwise direction to allow valve 10 to close even though toggle 22 is still in the over-

center position. Spring 33 causes the toggle to assume the undercenter position as soon as spring means 19 are released. Similarly, spring means 26 causes pivotally mounted member 25 to assume the position shown in Figs. 1 and 2 as soon as the closing operation of the valve has occurred. In Fig. 3, the apparatus is disclosed at the instant of closing when spring 33 has caused toggle 22 to assume the undercenter position but before spring 26 has caused pivotally mounted member 25 to assume the position assumed in Figs. 1 and 2.

It will be observed that high-speed closing of valve 10 may occur at any time regardless of whether or not the opening operation of the valve has been completed. Furthermore, motor 34 and crank 35 may continue to rotate after the valve has been fully opened in view of the fact that valve 10 is generally open for a relatively short time, consequently, motor 24 will be deenergized when solenoid 29 is deenergized. If it should be desirable to keep valve 10 open for a longer period of time, it will be obvious to those skilled in the art that a suitable cut-off switch for motor 34 could be provided as soon as toggle 22 reached its overcenter position; for example, a suitable cut-off switch could be associated with the extension 23' of toggle link 23.

While I have shown and described a particular embodiment of my invention, it will be obvious to those skilled in the art that various changes and modifications may be made without departing from my invention and I, therefore, aim in the appended claims to cover all such changes and modifications.

What I claim as new and desire to secure by Letters Patent of the United States is:

1. In combination, a valve having an operating stem, spring means associated with said stem for urging said valve to the closed position, a pivotally mounted member, a toggle having one end thereof connected to said member, the other end of said toggle being operatively connected with said valve stem, electromagnetic means for holding said pivotally mounted member in fixed relationship so that said valve may be opened against the force of said spring means when said toggle is moved to its overcenter position, and means for deenergizing said electromagnetic means to release said pivotally mounted member so that closing of said valve independently of said toggle is obtained.

2. In combination with a valve for controlling the flow of fluid, spring means operatively connected with said valve to bias said valve to the closed position, a pivotally mounted member, an electromagnetic latch for holding said pivotally mounted member stationary when said electromagnetic latch is energized, a toggle operatively connected between said pivotally mounted member and said valve, motor-operated means for opening said valve by exerting a force on said toggle to move said toggle to the overcenter position against the force of said spring means, and means for closing said valve regardless of the position of said toggle and independently thereof upon deenergization of said electromagnetic latch and consequent release of said pivotally mounted member.

3. In combination, a valve having an operating stem, spring means associated with said stem for urging said valve to the closed position, means for producing opening movement of said valve, a collapsible thrust-transmitting structure interposed between said last-mentioned means and

said operating stem, locking means for maintaining said valve in the open position against the force of said spring means, and latching means associated with said collapsible thrust-transmitting structure and arranged upon release to cause collapse of said thrust-transmitting structure and permit closing of said valve independently of said locking means or said means for urging the valve to the closed position.

4. In combination, a valve having an operating stem, spring means associated with said stem for urging said valve to the closed position, means for producing opening movement of said valve, a collapsible thrust-transmitting structure interposed between said last-mentioned means and said operating stem, locking means for maintaining said valve in the open position against the force of said spring means, and magnetic latching means associated with said collapsible thrust-transmitting structure and arranged upon release to cause collapse of said thrust-transmitting structure and permit closing of said valve independently of said locking means or said means for urging the valve to the closed position.

5. In combination, a valve having an operating stem, a spring associated with said stem for urging said valve to the closed position, means for producing opening movement of said valve against the force of said spring, a collapsible

thrust-transmitting linkage interposed between said last-mentioned means and said operating stem, and means for rendering said collapsible thrust-transmitting linkage effective or ineffective with respect to transmitting the force from said first mentioned means to said valve stem, said means for rendering said thrust-transmitting linkage effective or ineffective being so constructed and arranged as to permit closing of said valve independently of said first-mentioned means.

6. In combination with a valve for controlling the flow of fluid, a spring operatively connected with said valve to bias said valve to the closed position, a motor for producing opening movement of said valve against the force of said spring, a collapsible thrust-transmitting linkage interposed between said motor and said valve, and magnetic means for rendering said collapsible thrust-transmitting linkage effective to transmit force from said motor to cause opening of said valve, and means for causing said magnetic means to render said collapsible thrust-transmitting linkage ineffective so that closing of said valve at high speed may occur independently of the position of said motor or of said collapsible thrust-transmitting structure.

CARL THUMIM.
